(57) **CLAIM**

We claim the ornamental design for a double telescoping tongue, as shown and described.

DESCRIPTION

FIG. 1 is a perspective view of a double telescoping tongue in a closed position.

FIG. 2 is a top plan view of the double telescoping tongue in a closed position.

FIG. 3 is a bottom plan view of the double telescoping tongue in a closed position.

FIG. 4 is a side elevation view of the double telescoping tongue in a closed position.

FIG. 5 is a perspective view of the double telescoping tongue in an open position.

FIG. 6 is a top plan view of the double telescoping tongue in an open position.

FIG. 7 is a bottom plan view of the double telescoping tongue in an open position; and,

FIG. 8 is a side elevation view of the double telescoping tongue in an open position.

The subject matter shown in broken lines in the drawings are unclaimed features of the article in which the claimed design is embodied.
